UNITED STATES PATENT OFFICE.

ALBERT A. JAHNKE, OF POINT RICHMOND, CALIFORNIA, ASSIGNOR TO NATIONAL WIRELESS TELEPHONE & TELEGRAPH CO., OF SAN FRANCISCO, CALIFORNIA, A CORPORATION OF ARIZONA.

APPARATUS FOR THE PRODUCTION OF HIGH-FREQUENCY OSCILLATING CURRENTS.

1,115,823.

Specification of Letters Patent.

Patented Nov. 3, 1914.

Application filed June 11, 1912. Serial No. 703,082.

To all whom it may concern:

Be it known that I, ALBERT A. JAHNKE, a citizen of the United States, residing at Point Richmond, in the county of Contra Costa and State of California, have invented new and useful Improvements in Apparatus for the Production of High-Frequency Oscillating Currents, of which the following is a specification.

10 This invention relates to an apparatus for the production of high frequency oscillating currents by which wireless telephoning, telegraphing, etc., may be carried on.

It is the object of the invention to construct an apparatus for the production of high frequency oscillating currents from a direct current supply; said apparatus being capable of maintaining and discharging continuous and uniform undamped oscillations of very high frequency and force.

20 Another object of the invention is to provide means for automatically starting the oscillations and maintaining the uniformity and persistency of the same by regulating and keeping the electrodes of the apparatus at the proper distance, so that if for any reason the oscillations are broken between the electrodes, which may be caused by too much current, the wasting away of the electrodes, or a spark gap being too large, etc. the oscillations are started again, as herein specified.

25 The invention consists of the parts and the construction and combination of parts as hereinafter more fully described and claimed, having reference to the accompanying drawings, in which—

30 Figure 1 is a diagrammatic view showing the different apparatus employed in the wireless telephone system. Fig. 2 is a front elevation of my apparatus showing the units employed. Fig. 3 is a plan view of same. Fig. 4 is a side elevation, partly in section. Fig. 5 is a perspective and Fig. 6 is a section of a carbon electrode. Fig. 7 is another form of carbon.

35 The essential feature of this apparatus is the formation of a spark gap apparatus having interspaced terminal electrodes with substantially parallel opposed faces, submerged in an imperfectly conducting liquid, and acting to constantly change the position of the spark between the electrodes.

The apparatus consists of a container and means therein for the production of an electric spark discharge, which is maintained between parallel electrode faces which are submerged in an imperfectly conducting liquid medium in such a manner that constant circulation of the medium takes place around the electrodes. This medium is of such a nature that when heated its resistance increases, thereby causing the point of sparking between the electrodes to continually change, causing the surfaces of the electrodes to burn evenly so as to produce a constant and uniform distance between the surfaces of the electrodes.

In Fig. 1 of the drawings I have shown the connection and position of my apparatus in relation to the other instruments used in a wireless telephone system, in which A is a direct current generator, connected in series with a solenoid magnet B, a choke coil C, the high frequency oscillators and a choke coil E, and a variable resistance G, which connects with the negative pole of the generator A, thus completing the direct current supply circuit.

The primary oscillating circuit consists of a condenser D, in series with the primary coil of a high frequency transformer, connected across the terminals of the oscillators; said oscillating circuit being shown by heavy lines, to distinguish it from the current supply circuit, in which the solenoid magnet is placed.

40 As shown in the present drawings, 1 is a vertically disposed cylinder, provided with a bottom 2, and a base flange 3. The outside of the cylinder is provided with a water-jacket 4. The cylinder is provided with a perforated cover 5, in which is placed an insulating bushing lined with a metal bushing 7, through which passes a rod 8 carrying a metal cap 9, provided with an elastic holder 10, in which a carbon electrode 11 may be placed.

45 12 is a hollow metal cylinder provided with a flange 13, and threaded extension 14 screwed into a hollow threaded projection 15, extending from the bottom of the main cylinder.

50 17 is a screw cap adapted to close the lower end of the cylinder projection 15. This is provided with two metal tubes as

19 and 20, through which a circulating cooling medium as water, may be forced into the hollow cylinder 12.

In oscillating apparatus of this construction it has been proven by actual practice that at least one of the electrodes should be of metal, as these conserve their shape to a higher degree than carbon electrodes, which is of great importance for the stability and uniformity of the spark. Likewise, it is often advantageous to use electrodes of metal, as they are better heat conductors, and therefore quickly lead off heat from the spark. With this object in view, I have provided the hollow metal cylinder 12 as the positive electrode. The circulation of the cooling liquid within the hollow metal electrode 12 may be effected by connecting the tube 19 with a non-conducting water supply pipe 21. The water discharges from the end of the tube 19, as shown in Fig. 4, direct against the head of the electrode, or the sparking surface, carrying away any excess heat that may be generated there. The water discharges from the hollow electrode 25 through pipe 20, which in turn connects at 23 with the water-jacket of the cylinder, circulates through this to cool the liquid within the cylinder, and discharges through a 30 pipe 24, which connects with a manifold or discharge pipe 25, which will conduct the waste water away from the apparatus. The cylinder 2, is filled with an imperfectly conducting liquid in which the electrodes are 35 entirely submerged. The spark in jumping from one electrode to another, will cause a heating of the liquid at that point. The liquid being of a nature which, when heated, produces a greater resistance than, when 40 cooled, will cause the next discharge to seek the point of least resistance between the two electrodes, which will be the point where the liquid is most cool, thereby causing the spark to constantly shift and change its position.

By constantly changing the sparking point, the carbon does not pit and is burned or wasted very evenly and the frequency of oscillation as well as the volume of electric energy, is persistent and uniform.

The transmitter may be connected in series with the ground circuit of the secondary of the high frequency transformer, or it may be bridged across said secondary or a portion thereof, and will, when spoken into, disturb the high frequency current discharge of the antennæ, and thereby produce articulated sound in the receiver at some other station.

It can thus be seen that it is very necessary in an apparatus of this nature to produce oscillations of high frequency and regularity. If this frequency and regularity is interrupted or changed, by reason of the 60 irregularity of the sparking point, caused

by pitting, etc., it will tend to render vocal or other sounds which are dependent upon such regularity, confused and indistinct.

In the apparatus shown in the drawings, I employ three units connected in series and adapted to be operated in unison; the separate spark gaps of the set being controlled automatically by the following mechanism: B is a solenoid magnet connected in series with the main circuit, as already described, 70 which energizes an armature 27 connected to a lever 28 which is pivoted at 29 to a suitable frame as 30, mounted on the main base plate. The opposite end of the lever is forked, as shown in the plan view of the 75 drawings, and adapted to engage with a plate 31 having standards 32, which are provided with shoulders 33, and guide extensions 34, which project through a plate 35 carrying a plurality of clutches 36. The 80 clutch-carrying plate 35 is supported on standards 37 mounted on the base plate and is adapted to be raised or lowered, whichever the case may be, being guided by extensions 37^a on the standards. 90

The carbon-carrying rod 8 projects through the insulating bushing 7 in a perforated cover of the cylinder, extending upwardly a considerable distance and passes through plate 31, clutch 36 and plate 35. 95 Slidable on the rod is a cone 38 engageable with a set of arms 29 pivoted at 40 in the clutch. Interposed between the plate 35 and the cone 38 is a helical spring 40. The carbon-carrying rod is insulated from the 100 above mechanism by separating the rod 8 at 41 and placing a fiber connection between the two ends.

The operation of this part of the mechanism will be as follows: The solenoid magnet when energized will attract the armature 29, which being connected with the lever 28 will rock this on its pivot 29 and cause the opposite end of the lever to engage with the plate 35 and lift this a pre-determined distance. The raising of the plate 105 110 causes the springs to compress and forces the cones 38 up between the arms, spreading these so as to grip the rods. By the time the rods have been gripped by the clutches, 115 the shoulder 33 of the standards 32 will engage the plate 35 and raise the plate, clutches and carbon-carrying rods, thus separating the electrodes to produce the spark gap. The distance or space between the electrodes 120 can be regulated to produce the best result by an adjustable stop 42 mounted on the solenoid magnet. In order to prevent any shock or sudden movement of the different parts of the electrode elevating mechanism 125 when the magnet becomes energized, I have connected the lever with a dash-pot as 43, of any suitable or well-known construction.

To return the parts to inoperative position, I have provided a spring 44 connected 130

to the lever, which will retract the lever and allow the plate 31 to return, relieving the tension on the springs and allowing the cones to retract, which causes the clutch 5 arms to release the rods and permit the electrodes to re-seat and adjust themselves. By employing several units, the voltage of the current can be increased in proportion to the resistance produced by increasing the 10 number of units, thereby producing a high pressure current discharge through the oscillation circuit.

In operation it is frequently found that certain irregularities in oscillations are 15 caused by undesirable movements of the liquid in which electrodes are submerged. I have found that this may be overcome by perforating or subdividing the carbon electrodes so as to allow a free flow of the liquid 20 in the direction of the axis of the carbon. This may be effected by perforating the face of the carbons with one or more holes which may lead out through the sides of the carbon to insure a circulation of the liquid, 25 or by a number of small independent carbons.

As shown in Figs. 5 and 6, the openings or passages are shown in the form of slots 47 which may cross each other and have 30 their lower ends diverging as at 48. It will be understood that these carbons may be made in various forms to attain the desired result and provide for a smooth movement of the liquid. Fig. 7 shows the carbon in 35 the form of independent pencils with intermediate spaces.

Having thus described my invention, what I claim and desire to secure by Letters Patent is—

40 1. A spark gap apparatus having electrodes with opposed terminal faces parallel with each other, the terminal face of each electrode being substantially in a single plane and of large area to permit the shifting 45 of the spark parallel with the planes of the faces without variation in its length and frequency, means for automatically separating and spacing the electrodes to form the spark gap, and an imperfectly conduct- 50 ing liquid in which the electrodes are submerged, the resistance of which liquid increases as its temperature rises whereby as the spark increases the temperature of the liquid it is caused to shift from place to 55 place between the terminal faces.

2. A spark gap apparatus having electrodes with opposed terminal faces parallel with each other, the terminal face of each electrode being substantially in a single 60 plane and of large area to permit the shift-

ing of the spark parallel with the planes of the faces without variation in its length and frequency, one of said electrodes being of carbon and the other of said electrodes being of metal and having an internal chamber for 65 the circulation of a cooling medium, means for circulating a cooling medium through said last mentioned electrode, and an imperfectly conducting liquid in which the electrodes are submerged, the resistance of 70 which liquid increases as its temperature rises, whereby as the spark increases the temperature of the liquid it is caused to shift from place to place between the terminal faces. 75

3. A spark gap apparatus having electrodes submerged in an imperfectly conducting liquid, said electrodes having parallel opposed surfaces, one of said electrodes having its surface sub-divided, said subdivisions 80 having their surfaces forming the face of the electrode opposed and equidistant from the surface of the other electrode.

4. An oscillatory circuit spark gap apparatus including opposed interspaced circuit 85 terminal electrodes having opposed surfaces substantially parallel, a container in which said electrodes are removably mounted, a liquid cooling and circulating system connecting with said container within which the 90 electrodes are submerged, means for starting the oscillations and adjusting and spacing the electrodes with relation to each other, said means including clamping arms adapted to engage and lift one of the electrodes, a 95 solenoid magnet capable of being energized, a lever connected with the core of said solenoid and means actuated thereby, adapted to engage and lift the movable electrode.

5. An oscillatory circuit spark gap apparatus including opposed interspaced circuit 100 terminal electrodes with substantially parallel opposed surfaces, a chamber containing an imperfectly conducting liquid within which said electrodes are submerged, a rod 105 movable in line with the axes of the electrodes and by which one of said electrodes is carried, clamping arms and a cone by which said arms may be caused to grasp the rod, a solenoid and lever connection by which the 110 cone is engaged with the arms, and a spring by which the cones are moved to release the clamps when the solenoid is de-energized.

In testimony whereof I have hereunto set my hand in the presence of two subscribing 115 witnesses.

ALBERT A. JAHNKE.
